SMOKING PIPE

William B. Bush, Knoxville, Tenn.

Application December 24, 1936, Serial No. 117,644

3 Claims. (Cl. 131—210)

This invention relates to an improvement in smoking pipes.

The object of the invention is to effectively remove the nicotine from the smoke before the same reaches the smoker's mouth by the use of a simple and inexpensive attachment, and to cool the smoke to a substantial degree.

In the preferred embodiment of this invention, the removal of nicotine is accomplished by means of troughs, arranged in tandem in the path of the smoke, and each having transversely overlapped fingers arranged in staggered relation and laterally spaced from each other to admit the smoke approximately throughout the length of the trough to catch and hold the nicotine as the smoke passes through these troughs, so as to prevent this nicotine from being carried by the smoke to the user's mouth. One of these troughs is attached to the stem while the other is inserted into the lower portion of the pipe by means of a knob that may be withdrawn to facilitate cleaning of the trough and removal of the nicotine therefrom. This knob is provided with a slot which communicates with the smoke passage so that upon turning the knob the passage may be closed to prevent any nicotine from draining into the stem from the lower portion of the bowl or the lower trough, when the pipe is being carried in the pocket.

The smoke is cooled by being directed through a zigzag passageway, one portion of which is in the nature of a back draft passage leading to the stem, so that there is not a direct draft on the nicotine that forms in the bottom of the pipe, and so that the smoke travels through a passage of substantial length before reaching the stem, thus providing a cool dry and free smoke.

A preferred embodiment of the invention is illustrated in the accompanying drawing in which:

Fig. 1 is a longitudinal sectional view through the pipe;

Fig. 2 is a transverse sectional view therethrough on the line 2—2 of Fig. 1;

Fig. 3 is a disassembled perspective view of the lower trough and its knob;

Fig. 4 is a transverse sectional view therethrough on the line 4—4 of Fig. 3; and

Fig. 5 is a detached perspective view of the back draft tube.

The pipe illustrated is provided with the usual bowl 1, having an enlarged projecting portion 2 for attachment of the usual stem 3.

The enlarged portion 2 is preferably elongated in cross section as shown in Fig. 2, and is pro-

vided with parallel openings or passageways 4 and 5, of which the passageway 5 has a closed inner end, but receives the end of the stem 3 in its outer end. The passageway 4 extends directly from the bottom of the bowl 1, being restricted at 4', and has its outer end communicating with the inner end of the passageway 5, through a back draft passage 6 having a tube 7 therein to line the passage 6. This tube 7 is provided in order to drain any nicotine which may get into the back draft passage or into the upper passageway 5, back into the lower passageway 4, so as to keep it out of the stem. The passageways 4 and 5 may be cleaned by inserting an ordinary pipe cleaner therein.

The outer end of the passageway 4 is closed by means of a tubular knob 8, the outer end of which is closed and enlarged to form a head 9 to limit the insertion of the knob 8 and to permit its withdrawal. The tubular knob 8 is provided with a longitudinal slot 10 in position to register with the back draft passage and the lower passageway 4, but upon turning the knob 8, this communication may be cut-off and the back draft passage 6 closed in order to keep any nicotine that may be in the lower passageway from running into the upper passageway when the pipe is being carried in the pocket in an inverted position.

Located in the passageways 4 and 5, are metallic troughs or tubes 11 and 12, each of which is constructed substantially as shown in Fig. 3, being provided with laterally spaced transversely overlapped fingers 13 arranged in staggered relation in the sides thereof with spaces therebetween for flow of smoke into the trough approximately throughout its length, and each trough has a substantially cylindrical portion 14 inserted respectively into the tubular knob 8, and the inner end of the stem 3 in order to support these troughs respectively.

Each trough is shown as formed of sheet metal bent approximately into semicylindrical shape throughout the major portion of its length, except the cylindrical portion 14, the fingers being turned in as shown. This provides a substantial space at the top of each passage 4 and 5, so that the smoke accumulating in this space approximately throughout the length of the trough, except the portion 14, will be drawn into and through the trough to trap the nicotine therefrom. The lower peripheral portion of the trough is spaced from the adjacent portion of the passageway 4 or 5, as shown in Figs. 1 and 2, so as to permit smoke to come into contact with

the peripheral surface of the trough throughout substantially its entire length, except the portion 14. The staggered relation of the fingers permits smoke to enter the trough not only from 5 one end thereof, but also permits the smoke which circulates about and in contact with the outer peripheral surface of the trough approximately throughout its length, to find access to the inside of the trough at any point in the length 10 thereof except at the cylindrical portion 14.

As the smoke passes through the troughs 11 and 12, through the spaces between the fingers 13, the troughs will tend to remove from the smoke any nicotine contained therein, which will 15 be received and held in the troughs until the latter are removed and cleaned. The tandem relation of the troughs gives a double check on the nicotine preventing it from reaching the mouth with the smoke. The lower trough may 20 be removed by the removal of the knob 8, for effective cleaning thereof and of the passageway 4, of any accumulation of nicotine, while the upper trough may be removed with the stem for effective cleaning. Likewise the back draft 25 tube 7 can be cleaned with an ordinary pipe cleaner through the outer end of the lower passageway 4 upon removal of the knob 8. In this way, substantially all of the nicotine is effectively removed from the smoke and prevented 30 from reaching the mouth.

By providing the zigzag passageway for the smoke, including the back draft passage 6, the smoke passes through a substantial length of stem, approximately two inches more than would 35 be provided otherwise, and this helps to cool the smoke before it reaches the mouth. This back draft is not a direct pull on the burning tobacco in the bowl, so that it keeps the pipe cool and dry and the draft is not on the nicotine that 40 forms in the bottom of the pipe, thus smoking freely and providing a cool dry smoke.

The tube 7 and troughs 11 and 12 preferably 45 are constructed of aluminum for lightness in weight and efficiency in use being a porous metal. However, other suitable light weight metals or other materials may be used, if desired, for one or more of these metallic elements.

I claim:

1. In a smoking pipe comprising a bowl having 50 a side projection thereon for connection with a stem, said projection having a passageway therein leading from the bowl, a trough mounted in said passageway, said trough having its side walls provided with transversely overlapped fin-

gers at the upper edges thereof and approximately in a plane where said side walls are at their greatest distance apart and spaced from the adjacent portion of the passageway, said fingers being arranged in staggered relation and laterally spaced from each other for the passage of smoke into said trough approximately throughout the major portion of the length thereof to trap nicotine from the smoke. 5

2. In a smoking pipe comprising a bowl having 10 a side projection thereon and a stem connected with said projection, said projection having a passageway therein leading from the bowl to the stem, a hollow knob inserted into an end portion of the passageway and constituting part 15 of the passageway for the smoke, said knob having a slot through which smoke can pass from the knob to the stem, and a trough carried by said knob in the passageway and spaced from the sides thereof approximately throughout the 20 length of said trough, said trough having transversely overlapped fingers arranged in staggered relation and laterally spaced from each other for the passage of smoke into said trough approximately throughout the length thereof to 25 trap nicotine from the smoke.

3. In a smoking pipe comprising a bowl having a side projection thereon, said projection having approximately parallel passageways therein with an inclined back-draft passage extending from 30 the outer end of the lower passageway to the inner end of the upper passageway, said lower passageway having communication with the bowl, and a stem connected with the outer end of the upper passageway; a hollow knob rotatably and 35 removably inserted into the outer end of the lower passageway beyond the adjacent end of the back-draft passage and forming a closure for said lower passageway, said knob forming a passageway for smoke and having a longitudinal 40 slot therein in position to control communication through said back-draft passage, and a trough carried by said knob and extending in said lower passageway in spaced relation to all sides thereof approximately throughout the length of said 45 trough, said trough being approximately U-shaped in cross-section with transversely overlapped fingers arranged in staggered relation and laterally spaced from each other for the passage of smoke into said trough approximately throughout the length thereof to trap nicotine therein 50 from the smoke.

WILLIAM B. BUSH.
